UNITED STATES PATENT OFFICE.

KARL SCHMIDT, OF NEURUPPIN, GERMANY.

PORTABLE LIQUID-FIRE EXTINGUISHER.

Application filed July 8, 1927, Serial No. 204,313, and in Germany April 24, 1926.

This invention relates to a portable liquid fire extinguisher of that type in which the air space within the extinguisher is in communication with the outer air by means of a U-shaped pipe passing from the air chamber along the discharge pipe, for the purpose of preventing the liquid being driven out of the apparatus by the expanding enclosed air.

In the known fire extinguishers of this type the narrow pressure compensating pipes possessed a uniform cross-section throughout their length. The consequence was that after raising the apparatus from the charging position into the storage position the liquid which had penetrated into the pressure compensating pipes did not drain into the chamber located adjacent to the bottom of the apparatus, but pistons of liquid or freely suspended masses remained in the pipes which the low inner pressure within the extinguisher was incapable of forcing into the water seal chamber at the bottom of the extinguisher. The pistons of liquid thus choke the pressure compensating pipes and it was frequently found that extinguishers equipped with the known compensating devices yet showed the phenomenon known as "driving", by which is meant the unintentional discharge of liquid when the air pressure within the extinguisher increases.

According to the present invention this drawback is eliminated by not making the pressure compensating pipes of uniform cross-section throughout, but increasing the cross-section of a portion of them. The narrower portions of the pipes open into the air spaces to be connected, while the expanded portions of the pressure compensating pipes communicate with the water seal chamber. In this way the result is attained that at least the pressure compensating pipe located in the interior of the apparatus takes up a column of liquid which has a different cross-sectional area in correspondence with the different diameter of the pipe. When the apparatus is raised from the filling position into the storage position the portion of the column of liquid of larger cross-sectional area acts strongly drawing or sucking upon the portion of the column of liquid of the smaller cross-sectional area, so that the narrower part of the pressure compensating pipe is completely drained with certainty. No piston of liquid or freely suspended mass of liquid remains in the extended portion of the pressure compensating pipe, because the ad-

hesion of the liquid on the walls of the pipe does not suffice to hold a piston or short column of liquid. The pressure compensation pipes thus completely drain their contents into the water seal chamber when the apparatus is raised into the upright storage position, so that the channel or conduit placing the air space of the extinguisher in communication with the outer air may be relied upon to remain clear and unobstructed. In order to prevent the entry of large volumes of gas into the pressure compensating pipes when making use of the apparatus, the pressure compensating tube extending into the air space of the extinguisher is preferably closed by a nozzle-like extension provided with a comparatively fine admission opening. The cross-sectional area of this opening is smaller than the cross-sectional area of the part of the pipe upon which the closing member is placed.

The drawing affixed hereto illustrates in longitudinal section, a portable fire-extinguisher embodying the invention, both extremities being omitted. Although a conical apparatus is shown by way of example, it will be understood that the invention may, of course, be applied to other designs of extinguishers.

Referring to the single figure of the drawing, *a* is the fire-extinguisher and *b* its discharge or squirting pipe. The squirting nozzle and the closing members of the extinguisher have been omitted as they are well known. The filling opening is shown at *i*. In the interior of the apparatus there are located the pressure compensating pipes *d* and *e*. The pipe *d* opens into the air space *f* of the extinguisher and the pipe *e* into the air space of the discharge pipe *b*. These tubes *d* and *e* are expanded or made of larger internal diameter in their lower portions *d*¹ and *e*¹, so that the lower portion of the pipe possesses a larger cross-sectional area than the upper portion. The pipe portions *d*¹ and *e*¹ open at their lower ends into the water seal chamber *c*. The end of the tube *d* located in the air space *f* of the apparatus terminates into a nozzle-like member *g* provided with a fine bore *h*.

Various changes and modifications may be made in the details of my invention without departing from its spirit or the ambit of my claims.

I claim as my invention:

1. In a portable liquid fire-extinguisher having pipes adapted to put the inner air

space in communication with the air space of the discharge pipe and leading into a chamber located near the bottom of said extinguisher, pipes of larger diameter joined to said chamber and of smaller diameter opening into said air spaces.

2. In a portable liquid fire-extinguisher having pipes adapted to put the inner air space in communication with the air space of the discharge pipe and leading into a chamber located near the bottom of said ex-

tinguisher, pipes of larger diameter joined to said chamber and of smaller diameter opening into said air spaces, and a nozzle-shaped member mounted upon the admission opening of the compensation pipe located in the air space of the extinguisher, the cross-sectional area of said opening being smaller than the least cross-sectional area of its compensation pipe.

15

In testimony whereof I affix my signature.

KARL SCHMIDT.
